WILLIAM R. EICHENSER, OF JOHNSTOWN, PENNSYLVANIA.

SAFETY DEVICE FOR ENGINES.

1,391,724.

Specification of Letters Patent. Patented Sept. 27, 1921.

Application filed October 7, 1920. Serial No. 415,290.

To all whom it may concern:

Be it known that I, WILLIAM R. EICHENSER, a citizen of the United States, and a resident of the city of Johnstown, in the county of Cambria and State of Pennsylvania, have invented certain new and useful Improvements in Safety Devices for Engines; and I do hereby declare the following to be a full, clear, and exact description of the invention, such as will enable others skilled in the art to which it appertains to make and use the same.

My invention relates to a safety device for automatically reducing the speed of an engine when the engine governor fails to function and the engine thereby tends to run away with its load, and is particularly adapted to stationary engines which have a belt driven throttling governor.

Engines subjected to variable loads as for instance, in rolling mill operations, where no load to full load changes frequently occur, and controlled by belt driven governors will run wild if the governor belt breaks, slips or runs off the pulleys. In the event of such conditions the fly wheel will acquire so great a speed that the resultant centrifugal force exceeds the static strength of the material of which the fly wheel is made, with disastrous effects to life and property.

The object of my invention is therefore to prevent an engine from running away with its load when the governor belt breaks, slips or runs off the pulleys by an automatic means adapted to throttle the engine down without any human attention and at the same time to operate a whistle or other alarm to announce the trouble.

My invention comprises a weighted stop rod normally held in position by a trip so as to be clear of the engine admission valve reach rod and a weighted trip lever provided with an idler pulley which rides on the governor belt, thereby holding the trip lever in normal position. The weight on the trip lever is sufficient to cause the idler pulley to act normally as a belt tightener for the governor belt, but if the governor belt breaks or runs off the pulleys, the trip lever drops, thus disengaging the trip and allowing the weighted stop rod to drop onto the admission valve reach rod. This lowers the admission valve reach rod in the eccentric link slot and the valve is thus thrown into the position of minimum admission, thereby slow-

ing the engine down and preventing it from running wild.

My invention further comprises a cable connected to the stop rod and to a whistle on the steam line, so that when the stop rod drops it pulls on the cable and blows the whistle to audibly announce the trouble.

Having thus given a general description of my invention, I will now, in order to make the matter more clear, refer to the annexed sheet of drawings, which forms part of this specification and in which like characters of reference refer to like parts:

Figure 1 is a side elevation of a steam engine showing the embodiment of my invention therewith;

Fig. 2 is a transverse sectional view to a larger scale, taken on line II—II of Fig. 3; and

Fig. 3 is an enlarged side elevation of the right hand portion of Fig. 1, showing the embodiment of my invention in detail, the governor pulley and crank shaft of the engine being shown in section and the flywheel omitted.

Referring now to the characters of reference on the drawings: 1 indicates the engine frame and 2 the crank shaft on which the eccentric 3 is mounted. The governor belt 4 passes around the crank shaft 2, by which it is driven, and drives the governor pulley 6, which is secured to the governor drive shaft 5.

The lever 7 is fulcrumed on the pin 41 so as to turn freely thereon and carries at one end of the shaft 9 the idler pulley 10 which rides on the governor belt 4, and the weights 12 on the rod 11, which is suspended from the trip lever 7, cause the idler pulley 10 to act as a belt tightener for the governor belt 4, thus maintaining the trip lever 7 in the normal or running position and preventing slip of the governor belt. The trip lever 7 is provided with the lug 8.

The trip 13 is provided with the tripping point 14 with which the lug 8 is adapted to forcibly contact, and the catch 15 which normally engages the lug 16 on the stop rod 17, holds the stop rod 17 in the raised position as shown.

The stop rod 17 is guided in the frame 40 and carries the weights 18. The upper end of the stop rod 17 is bent into hook form and is normally clear of the admission valve reach rod 38. Slots 21 in the upper end of

the stop rod 17 guide the axle 20 of the wheel 19. There is also mounted in the upper end of the stop rod 17 just above the wheel 19 a shock absorbing or cushioning device comprising the spring 22 and the bearing plate 39. 32 as shown in dotted lines in Fig. 3 indicates the stop rod 17 of extended length as adapted to my device when applied to steam engines equipped 5 with the Corliss type of valve gear. In any case if preferable or necessary the stop rod 17 can be made of sufficient length so that the hooked end thereof can extend over the governor control lever 28. 3 is the exhaust 10 valve reach rod of the valve gear shown and is adapted to operate the exhaust valve with constant release and compression.

23 indicates the shoe or slide block of the admission valve reach rod 38 and the shoe 20 23 moves in the slotted link 24 of the eccentric strap. The shoe 23 is hinged to the admission valve reach rod 38 and the floating link 26 by the pin or bolt 25 and accordingly as the shoe 23 is raised or lowered in the 25 slotted link 24 of the eccentric strap, the admission valve cut off is retarded or advanced, thereby varying the time of admission so as to maintain the speed of the engine to the power requirements. The governor 31 acting on the control lever 28 which carries the counterweight 30 and is fulcrumed to the governor frame by the pin or bolt 29 and to the floating lever 26 by the pin or bolt 27, ordinarily operates to raise or lower the shoe 23 through the floating link 26, thereby controlling the engine speed.

37 is the inlet valve on the steam line. 36 40 is a whistle connected to the steam line and a cable 34 extends from the lever of the whistle 36 over the sheave 35 to the top of the stop rod 17.

Assuming the position of the parts to be as shown in the drawings, the operation of my engine safety device is as follows: the 45 parts as shown are in the normal or operating position, the trip lever 7 being held in place by the governor belt 4 and the stop rod 17 by the lug 16 in engagement with the catch 15 of the trip 13. If the governor belt 50 4 breaks or runs off the pulley 6 the trip lever 7 is pulled down by the weights 12, which are made sufficiently heavy so that the lug 8 on the trip lever 7 will contact with the tripping point 14 of the trip 13 with force 55 enough to disengage the catch 15 from the lug 16 on the stop rod 17. The stop rod 17 is thereby released and the weights 18 pull it downward so that the wheel 19 contacts with the admission valve reach rod 38 with sufficient force to lower the shoe 23 to the 60 position of quickest cut off for the admission valve, thereby automatically slowing down the engine. The weights 18 are made heavy enough to pull the reach rod 38 down 65 into the lowest position against friction and

the weight of the governor 31 which will of course drop to its lowest position when the governor belt breaks or runs off the pulley. The weights 18 may, of course, be varied to insure the necessary force and in order that 70 there may be no shock sufficient to damage the mechanism the spring 20 in the upper part of the stop rod 17 is provided to ease off the dropping stop rod 17. As the stop rod 17 drops it pulls the cable 34 thereby 75 blowing the whistle 36 to announce the trouble with the belt.

By replacing or repairing the governor belt 4 and setting the idler pulley 9 on it and raising the stop rod 17 until the catch 80 15 on the trip 13 engages the lug 16, my device is again in position to function.

The advantages of my safety device are therefore evident, as it provides a positive automatic means which will prevent an engine from running away under no load or variable loads when the governor control fails to act. The action of my device is entirely automatic even to the alarm which gives notice of the trouble and my device is 90 comparatively economical to install.

Although I have described and illustrated my invention in considerable detail, I do not wish to be limited to the exact and specific details thereof, as shown and described, but may use such modifications in, substitutions for, or equivalents thereof, as are embraced within the scope of my invention, or 95 as pointed out in the claims.

Having thus described my invention, what 100 I claim and desire to secure by Letters Patent is:—

1. The combination with an engine governor of a safety device comprising a weighted stop rod having one end extending 105 over the admission valve reach rod of the engine, a trip adapted to hold said stop rod normally clear of said reach rod, and a weighted trip lever fulcrumed on the engine frame and having the weighted end thereof 110 normally supported by the governor belt whereby when the governor belt breaks the trip lever actuates said trip to release the stop rod which drops on to the admission valve reach rod, thereby lowering the same 115 and reducing the engine speed.

2. In combination with a steam engine, a safety device for reducing the speed of the same, comprising a weighted stop rod provided with an end adapted to engage the admission valve reach rod of the engine, a trip adapted to hold said stop rod normally clear of said reach rod, a weighted trip lever normally supported by the governor belt and adapted to release said trip when 120 the governor belt breaks, thereby dropping said stop rod on to said reach rod and causing the latter to decrease the period of admission.

3. In a steam engine the combination of an 130

admission valve reach rod adapted to vary the period of steam admission, a weighted stop rod provided with a hooked end extending over said reach rod, a trip adapted 5 to hold said stop rod normally clear of the reach rod, and a weighted trip lever having the weighted end thereof normally supported by the engine governor belt, said trip lever being adapted to release said trip when 10 the governor belt breaks, thereby dropping the stop rod onto the reach rod and lowering the latter to the point of minimum admission.

4. In combination with an engine and a 15 governor therefor, a device for reducing the speed thereof when the governor belt fails to function, comprising a stop rod provided with a hooked end extending over the admission valve reach rod of the engine, a trip 20 adapted to hold said stop rod normally clear of the reach rod, and a weighted trip lever having the weighted end thereof normally supported by the governor belt, said trip lever being adapted to release said trip when 25 the governor belt breaks, thereby dropping said stop rod on to said reach rod and throwing the admission valve of the engine to the position of the quickest cut-off.

5. In combination with an engine and a 30 governor therefor, a safety device comprising a lever, one end of which is fulcrumed on the engine and the other end provided

with a suspended weight and an idler pulley normally adapted to ride the governor belt, thereby acting as a tightener therefor, a 35 weighted stop rod having the upper end thereof bent into hook form and extending over the control lever of the governor, a trip normally adapted to hold said stop rod clear of the governor control lever and also 40 adapted to release said stop rod when the trip lever is dropped into forcible contact with the trip by the breaking or running off the pulley of the governor belt, thereby lowering the governor control lever and reducing 45 the speed of the engine.

6. The combination with the drive belt of an engine governor, of a safety device comprising a weighted trip lever having a projection thereon and provided with a pulley 50 normally adapted to rest on the belt and a stop rod provided with a pivoted trip adapted to cooperate with the projection on the trip lever, said stop rod having its upper end hooked over but normally clear of the 55 admission valve reach rod whereby when the governor belt breaks the trip lever disengages the trip and drops the stop rod on to the reach rod thereby lowering the same and reducing the speed of the engine. 60

In witness whereof I hereunto affix my signature.

WILLIAM R. EICHENSER.
